O. H. HUNT,
SIGNAL DEVICE FOR MOTOR VEHICLES.
APPLICATION FILED, FEB. 5, 1918.

1,279,114.

Patented Sept. 17, 1918.

Inventor
OTTO H. HUNT

By Esq. S. J. S. S.
Attorney.

UNITED STATES PATENT OFFICE.

OTTO H. HUNT, OF WALLA WALLA, WASHINGTON.

SIGNAL DEVICE FOR MOTOR-VEHICLES.

1,279,114.

Specification of Letters Patent. Patented Sept. 17, 1918

Application filed February 5, 1918. Serial No. 215,497.

To all whom it may concern:

Be it known that I, OTTO H. HUNT, a citizen of the United States, residing at Walla Walla, in the county of Walla Walla and State of Washington, have invented certain new and useful Improvements in Signal Devices for Motor-Vehicles, of which the following is a specification.

This invention relates to signal devices 10 employed in connection with motor vehicles, and designed to indicate and give timely warning to drivers of other vehicles, as well as to pedestrians, traffic officers, etc., at intersections of streets or other places, of contemplated changes in the course or direction of the car.

The invention has for its object to provide a simple and efficient device of the character stated, and one which is so arranged 20 that it will warn vehicles or pedestrians approaching from the front, the rear or either side, the device being specially valuable at street intersections for positively indicating to any approaching car the intended direction or course of the car carrying the signal.

The object stated is attained by means of a novel combination and arrangement of parts to be hereinafter described and claimed, and in order that the same may be 30 better understood, reference is had to the accompanying drawing forming a part of this specification.

In the drawing, Figure 1 is a plan view showing the application of the invention; Fig. 2 is a front elevation of the signal device; Fig. 3 is a cross-section on the line 3—3 of Fig. 1, and Fig. 4 is an elevation showing a slightly modified form of clamp.

Referring specifically to the drawing, 40 denotes an indicator arm carrying at its outer end a suitable illuminating device such as an ordinary incandescent electric lamp 6. The arm is an elongated, flat sheet metal plate, with its longitudinal edges rolled to obtain the necessary rigidity, and it is carried by a shank 7 having a flattened outer end portion 8 in the shape of an arrow, the same being riveted or otherwise fastened to the front face of the arm. An 50 arrow 9 may also be applied to the rear face of the arm.

The wiring for the lamp 6 is shown at 10, and may be seated beneath the rolled edge of the arm 5. The usual lamp globe and fixtures are used. The lamp casing 11 is suitably supported in an opening in the

arm 5 near the outer end of the latter, and it carries the usual lens fronts 12 to which is preferably added an arrow 13 blown into the glass. The lens may be of the usual 60 green, red or any preferred color.

The signal arm hereinbefore described is supported by the frame of the windshield of the car, and it is mounted so that it may be swung in a horizontal plane to point 65 straight ahead, or sidewise to the right or left of the car. The following supporting means are provided for this purpose:

A fragment of the windshield frame is shown at 14, and to this part is attached a 70 clamping member composed of two opposite jaws 15 and 16, respectively, which are drawn together by bolts 17 to grip said part 14. The inner faces of the jaws are suitably shaped to correspond to the cross-sectional contour of the part 14. If said part is rectangular, the jaws may be correspondingly shaped as shown in Fig. 4, the jaws being here denoted by the reference characters 75 15^a and 16^a.

The jaw member 15 has an inwardly projecting lug 18 at its rear end, said lug being triangular, with its apex engaging the rear portion of the jaw member 16. The purpose of this lug is to enable the jaw 15 to 85 be tilted with respect to the jaw 16 as shown dotted in Fig. 3, so that the clamp can be made to fit a windshield frame of almost any shape or size. In order that the jaw 15 may be tilted as described, the bolt holes 90 through which the bolts 17 pass are enlarged sufficiently to allow the necessary play.

The shank of the jaw 16 is formed with a circular, disk-like enlargement 19 and a threaded stem 20 extending rearwardly 95 therefrom. This stem supports a bracket arm 21 having a disk-like enlargement 22 at its inner end, provided with a perforation at the center so that it may be slipped over the stem, on which latter it is secured by a 100 nut 23. The parts 19 and 22 are clamped together by the nut, and in order to obtain a better hold, the contiguous faces thereof are serrated. The bracket arm 21 is therefore securely attached to the jaw 16 of the 105 windshield clamp, and it is adjustable angularly upon loosening the nut 23.

The outer end of the bracket arm 21 pivotally supports the hereinbefore described signal arm assembly, the outer end of the former having a circular head or enlargement 24 through which passes a bolt 25.

The inner end of the signal arm shank 7 also has a circular head, or enlargement 26 through which the bolt 25 passes. Under the head 27 of the bolt 25 is held a clip 28 for supporting the wiring 10. The bolt projects from the part 24, and on its projecting end is threaded a nut 29, with a spring 30 coiled around the projecting bolt end, between the part 24 and the nut, whereby the parts 24 and 26 are yieldably clamped together. The shank 7 is adjustable to set the signal arm 5 straight ahead or pointing sidewise to the right or the left, and in order to hold the shank in these three positions, the face of the part 26 which engages the part 24 has a lug 31 entering and seating in notches in the latter part, these notches corresponding in number and position to the different positions the shank may be set. The spring 30 has sufficient tension on the pivot joint to hold the shank in the position it may be set, its normal position being straight ahead, and when it is swung to point to either side, the lug 31 slips out of the notch in which it was seating, and when the shank arrives in the desired position, the lug slips in the proper notch. The necessary lateral movement of the part 26 with respect to the part 24 for permitting the hereinbefore described action of the lug 31 is obtained by having the bolt 25 passing loosely through the part 24. To facilitate the control of the signal arm 5, the part 26 has a projecting actuating arm 32. To the part 22 is anchored one end of a tension spring 33 having its other end connected to the part 26. This spring is arranged radially with respect to the pivotal axis of the part 26, and it is put under tension when the latter is rotated to bring the arm 5 into the side display positions as shown dotted in Fig. 1. A slight jar will disengage the lug 31, whereupon the spring 33 will bring the arm 5 back to straight ahead position automatically. When turning a corner to the left, the signal arm will be thrown to point to the left and it remains long enough in this position to warn any approaching vehicle. When a turn to the right is made, the signal arm will be thrown to point sidewise to the right to warn pedestrians or cars approaching from in front.

The normal position of the signal arm is straight ahead, in which position it remains as long as the car is going straight ahead. 55

On the parts 24 and 32 are coöperating stops 34 and 35, respectively, by which the maximum throw of the signal arm is controlled. These stops also prevent the signal arm from colliding with the windshield or being thrown to the right. There are two stops 34 although one only is shown in Fig. 1, the position of the other one being 60 covered by the wire 10. 65

It will be noted that the inner end of the shank 7 extends laterally with respect to the arm 5, this lateral portion being of such length that the arm clears the windshield and comes in front thereof when it is swung 70 over to point to the right as shown dotted in Fig. 1. The spring 33 is anchored to the laterally extending inner portion of the shank 7, and hence it is placed under tension when the arm 5 is swung in either direction 75 to display position.

I claim:

1. A vehicle direction signal comprising a signal arm normally pointing in a certain direction, a shank carrying the arm and having a laterally extending inner end which is pivotally supported to permit the arm to be swung to point sidewise in either direction from its normal position, and a tension member connected to the laterally 80 extending portion of the shank and arranged radially with respect to its pivot, said member being placed under tension when the arm is swung to point to either 85 sidewise position to restore the arm to normal position. 90

2. A vehicle direction signal comprising a signal arm mounted at the side of the vehicle and normally pointing straight ahead, said arm being pivotally supported 95 to swing in a horizontal plane for adjustment to point laterally to either side, and a tension member connected to the signal arm and arranged radially with respect to its pivot, and tending to restore the arm to the 100 first-mentioned position, said member being placed under tension when the arm is swung to point in the other directions.

In testimony whereof I affix my signature.

OTTO H. HUNT.
